ULTRA HIGH FREQUENCY ANTENNA

Robert S. Wehner, Port Jefferson, N. Y., assignor
to Radio Corporation of America, a corporation
of Delaware

Application November 26, 1945, Serial No. 630,925

2 Claims. (Cl. 250—33)

1

The present invention relates to ultra high frequency antennas and more particularly to such antennas particularly adapted for use on airplanes.

An object of the present invention is the provision of an ultra high frequency aircraft antenna having zero aerodynamic drag.

Another object of the present invention is the provision of an aircraft antenna capable of being entirely contained within the skin of the airplane.

A further object of the present invention is the provision of an antenna, as aforesaid, which has broad-band impedance characteristics.

Still a further object of the present invention is the provision of the antenna, as aforesaid, which is capable of more than 20% band width when operated in conjunction with lengths of commercially available coaxial transmission line.

Still a further object of the present invention is the provision of ultra high frequency aircraft antenna which has radiation characteristics making the antenna suitable for either vertically or horizontally polarized radiation.

Still another object of the present invention is the provision of an ultra high frequency aircraft antenna which has physical dimensions small enough to be practical at frequencies higher than 300 megacycles per second, even on the smallest aircraft.

Still a further object of the present invention is the provision of an ultra high frequency aircraft antenna of simple physical design of great inherent mechanical strength.

Still another object of the present invention is the provision of an ultra high frequency aircraft antenna which may be installed in aircraft without in any way weakening the structure or skin of the ship.

The foregoing objects and others which may appear from the following detailed description are attained by providing a cylindrical or semi-cylindrical sleeve radiator mounted coaxially in a semi-cylindrical cavity recessed in the skin of the plane. The internal walls of the cavity may be made of strong sheet metal while the aperture may be covered with a thin window of polystyrene, methylmethacrylate or other low loss dielectric material set flush in the skin of the ship.

While intended primarily for use on aircraft, it will be evident from the following description that the use of this antenna is readily extended to other vehicles and to fixed installations such as in the wall of a building or tower. In the latter type of installations, where the restrictions im-

2

posed on physical dimensions are not as severe as on aircraft, use of the antenna can be extended to frequencies much lower than 300 megacycles per second.

5 The present invention will be more fully understood by reference to the following detailed description in which:

Figure 1 shows in perspective an embodiment of the present invention, while

10 Figures 2, 3 and 4 are curves illustrating the impedance characteristics of an antenna similar to that of Figure 1 with different feeding means connected to the antenna.

Figure 5 is a schematic diagram illustrating the 15 arrangement of an elemental transmission line matching section for the antenna of Figure 1, while

Figure 6 is a plan view partly in section of the 20 antenna of Figure 1, showing the mechanical details of the matching section in more detail, and

Figures 7 and 8 are field strength patterns of the antenna of Figure 1.

Referring now to Figure 1, reference numeral 10 identifies the skin of a ship; that is, it is the 25 metallic outer casing of the fuselage of an airplane or it may be the upper or lower surface of one of the wings of the airplane. In the conductive sheet 10 is cut a rectangular aperture 12. A semi-cylindrical cavity is formed back of aperture 12 by a curved conductive rear wall 14 and semi-circular end plates 16 and 18. Aperture 12 is preferably closed by a thin window 12' of polystyrene or other low loss dielectric constant material so arranged flush with the outer surface of

30 conductive sheet 10. Thus, the entry of rain, snow or dust into the cavity is prevented and the electrical characteristics of the cavity maintained constant. One of the end walls, that is, end wall 18 has an aperture therein through which passes the outer sleeve 20 of a sleeve fed coaxial antenna. The upper half of the radiator is formed by rod radiator 21 which may be directly connected to the inner conductor 23 of coaxial transmission line TL. The outer shell 24 of transmission line

35 TL is directly connected to sheet 18 and also to sleeve 20. Dimensions of the system which have been successful are indicated in the drawing and are tabulated as follows:

40 Cavity length, approximately $\frac{3}{8}$ wavelength.

45 Cavity radius, $\frac{3}{16}$ wavelength to $\frac{1}{8}$ wavelength, depending upon whether a cylindrical or semi-cylindrical radiator is used.

Antenna length, approximately $\frac{1}{8}$ wavelength.

Sleeve length, approximately $\frac{3}{2}$ wavelength.

50 All of the wavelengths referred to being that

of the lowest frequency of the desired pass band, the dimension applying to an air-filled cavity.

For an antenna designed to cover the range of from 750 to 1,000 megacycles per second, the cavity dimensions may be as follows:

	Centimeters
Cavity length	15
Cavity radius	7.5
Maximum depth	10.2
Maximum width	15

Referring now to Figure 2 which is a curve showing the impedance characteristics of an antenna in a cylindrical cavity using a straight axial stub antenna, 7.6 centimeters long, and 0.9 centimeter in diameter, curve 30 illustrates the variation in input impedance as the input frequency is varied from 750 megacycles/sec. to 1,000 megacycles/sec. The region of less than 2:1 standing wave ratio on a 50-ohm line is delineated by dotted circle 31. It will be noted that the entire length of curve 30 is outside of the circle 31 showing that at no point is it possible to attain less than 2:1 standing wave ratio on a 50-ohm line with a simple stub antenna.

By adding a coaxial sleeve 3.8 centimeters long and 2.4 centimeters in diameter around the lower end of the stub radiator the impedance characteristics shown in Figure 3 are obtained. Curve 40, it will be noted, now passes through the circle 31 limiting the region of less than 2:1 standing wave ratio in the region between 800 to 880 megacycles per second. Thus, there is a 10% band width with less than 2:1 standing wave ratio, with the antenna fed directly from 50-ohm line, without recourse to matching circuits.

By further modifying the antenna to include a two element matching section in the sleeve, the characteristics in Figure 4 are obtained. Here curve 50 is within the dotted circle 31 for nearly its entire length. Therefore, a less than 2:1 standing wave ratio is obtained from 760 to nearly 920 megacycles, thus giving a 22% band width.

It will be further noted from reference to Figure 2 that the characteristics of a simple stub in a cylindrical cavity are marred by a low impedance level and by a steep variation of reactance with frequency. That is, the slope of curve 30 is excessively steep. In Figure 2 the addition of a sleeve surrounding the lower end of the radiator 21 results in the impedance level being raised, the resonant resistance now being 40 ohms as compared to 15 ohms for the stub antenna above. The rate of variation of reactance with frequency, as will be noted from the slope of curve 40, is decreased while the resonance is shifted upwardly some 40 megacycles toward higher frequencies.

The matching section which results in the improved characteristics shown in Figure 4 over those shown in Figure 3 is shown diagrammatically in Figure 5, while the structural details are shown in more detail in Figure 6. In Figure 5 the main transmission line from the source (not shown) is identified by reference letters TL', the said transmission line being connected to a series matching section 55 by means of a conventional type of line connector 56. In the case of a 50-ohm transmission line the series section may have an impedance of 60 ohms and be 81 electrical degrees in length at 760 megacycles. The other end of the series section is connected to the antenna indicated diagrammatically here by load resistor LR. At the junction between the

series section 55 and load LR there is connected a short circuited shunt section 57 acting as an anti-resonant shunt. Since the antenna is series resonant, the shunt section must be anti-resonant so that the rate of antenna input reactance with change of frequency is reduced by opposing variations of the shunt section. A particular embodiment of the invention constructed and tested used a shunt section having a characteristic impedance of 50 ohms and 270 electrical degrees in length at 885 megacycles. Short-circuited line sections of lengths equal to $1/4$, $3/4$, $5/4$, etc., wavelengths and open-circuited lines of lengths $1/2$, 1, $1\frac{1}{2}$, etc., wavelengths are practical anti-resonant circuits which may be used. The particular examples given are merely illustrative and not intended to be restrictive. The actual impedance values and the line lengths used in any particular construction may vary in dependence upon the antenna impedance and the line impedance. The antenna impedance in turn is dependent upon the cavity construction and operating frequency band.

The mechanical details of the two-element matching section are shown in more detail in Figure 6. Herein the matching sections 55 and 57 and the sleeve 20 associated with radiator 21 are shown in section. The matching section 55 may for example consist of a piece of coaxial line having its outer sheath 58 soldered or otherwise firmly electrically connected to the upper end of sheath 20. The inner conductor 59 of the matching section 55 is connected to the bottom end of radiator member 21. The shunt matching section 57 may consist of a piece of coaxial line of a length so as to be anti-resonant at the desired frequency with the inner conductor 61 and the outer sheath 62 connected together at one end by a short-circuiting means 63. At the other end outer shell 62 is electrically connected to the upper end of sheath 20 while the inner conductor 61 is connected to radiator member 21 in parallel with conductor 59. The junction between conductors 59, 61 and 21 may be entirely surrounded by solid dielectric material 64 to seal the junction between the line sections and the base of radiator 21. The dielectric material also serves as a support for the radiators. The dielectric material 64 is preferably polyethylene, a synthetic insulating material used as a solid dielectric between the outer shell and the inner conductor of most commercially obtainable coaxial transmission lines.

In Figure 7 the transverse section of the antenna shows a modified form of radiator and sleeve whereby the dimensions of the cavity may be further reduced. Radiator 21' and sleeve 20' are semi-cylindrical in section. Thus, the axis of the radiator and sleeve may be nearer the mouth of cavity 12.

Typical radiation patterns of the antenna of Figure 1 are shown in Figures 7 and 8. Figure 7 showing by means of radiation pattern 70 the field strength in a plane normal to the conductive sheet 10 and normal to the antenna 21. The plane of polarization of the radiated energy is parallel to the axis of the antenna while Figure 8 shows by means of radiation pattern 80 the distribution of energy in a plane normal to ground plane 10 and in a plane parallel to the antenna 21.

The distribution of radiation shown in Figures 7 and 8 may also be considered from the aspect of the installation of the antenna in an air-
75 plane. Suppose the cavity to be mounted on the

underside of the wing or fuselage of an airplane with the length of the cavity parallel to the line of flight, then the curve 70 of Figure 7 is an athwartship pattern for horizontal polarization and the curve 80 of Figure 8 is the vertical fore-and-aft pattern. It is evident from these figures that the radiation from a cavity antenna is entirely concentrated in the hemisphere toward which the aperture faces. The curves are predicated upon the assumption that the cavity is mounted in a surface having a radius of curvature not less than the length of an operating wavelength.

The impedance characteristics and field pattern characteristics of the antenna of the present invention make the antenna suitable for use in many applications. For example, in an altimeter installation two cavities may be used, mounted several wavelengths apart in the underside of a wing or fuselage with the cavity axes parallel, one cavity being used for transmission and the other for reception.

A single cavity mounted as mentioned above would be suitable for ultra high frequency guided missile control. A single cavity mounted in the tail of the plane with the aperture opening aft provides a very satisfactory pattern and ample band width for automatic tail-warning devices. Alternately, a single cavity mounted in the nose of the plane looking forward and slightly downward would be useful for identification systems. If it is desired to obtain a fairly complete coverage of space from an airplane a pair of antenna mounted on either side of the fuselage and fed in phase quadrature may be used while the addition of a third cavity mounted in the nose or the tail of the airplane, the three fed in a three-phase relationship, would result in a still more uniform pattern. Due to the compensation inherent in polyphase feed, these systems would have a greater band width than a single cavity.

As indicated above, the antenna of the present invention is usable for either transmitting or receiving service depending upon the type of radio frequency transducer means connected to the remote end of transmission line TL.

While I have illustrated a particular embodiment of the present invention, it should be clearly understood that it is not limited thereto since many modifications may be made in the several elements employed and in their arrangement and it is therefore contemplated by the appended claims to cover any such modifications as fall within the spirit and scope of the invention.

What is claimed is:

1. An ultra high frequency broad band antenna system including a conductive sheet having an aperture therein, a semicylindrical conductive structure arranged behind said aperture and connected to said sheet at its edges to define a hollow structure open at said aperture, a conductive sleeve member located within and having one end connected to said structure, said sleeve member extending concentrically of said structure, a conductive rod member arranged in end-to-end coaxial relationship to said sleeve member, and

means to extend a coaxial transmission line having inner and sheath conductors within said sleeve member and to connect the respective conductors to said rod and said sleeve members at the adjacent ends thereof, the length of said structure being substantially three-eighths of the longest wavelength of the desired pass band, and the radius being between three-sixteenths and one-eighth of said longest wavelength, the total length of said rod and sleeve members being substantially three-sixteenths of said longest wavelength and the sleeve member having a length of substantially three thirty-seconds of said longest wavelength.

15 2. An ultra high frequency broad band antenna system including a conductive sheet having an aperture therein, a semicylindrical conductive structure arranged behind said aperture and connected to said sheet at its edges to define a hollow structure open at said aperture, a conductive sleeve member located within and having one end connected to said structure, said sleeve member extending concentrically of said structure, a conductive rod member arranged in end-to-end coaxial relationship to said sleeve member, and means to extend a coaxial transmission line having inner and sheath conductors within said sleeve member and to connect said conductors respectively to said rod and said sleeve members at the adjacent ends thereof, the length of said structure being substantially three-eighths of the longest wavelength of the desired pass band, and the radius being between three-sixteenths and one-eighth of said longest wavelength, the total length of said rod and sleeve members being substantially three-sixteenths of said longest wavelength and the sleeve member having a length of substantially three thirty-seconds of said longest wavelength, and a further section of coaxial transmission line extending within said sleeve member and connected to said rod and sleeve members at the adjacent ends thereof, said coaxial transmission line section having a length at which adverse effects on bandwidth of said antenna are neutralized.
